DESIGN FOR A PORTABLE DRAINBOARD

Edwin F. Clark, Meriden, Conn.

Application February 9, 1948, Serial No. 144,378

Term of patent 3½ years

(Cl. D4—2)

To all whom it may concern:

Be it known that I, Edwin F. Clark, a citizen of the United States, residing in Meriden, county of New Haven, and State of Connecticut, have invented a new, original, and ornamental Design for Portable Drain Board, of which the following is a specification, reference being had to the accompanying drawing, forming part thereof.

Fig. 1 is a top view of a portable drain board showing my new design.

Fig. 2 is a longitudinal sectional view of the same, taken along the line 2—2 of Fig. 1.

Fig. 3 is a transverse sectional view of the same, taken along the line 3—3 of Fig. 1.

I claim:

The ornamental design for a portable drain-board, as shown.

EDWIN F. CLARK.
